UNITED STATES PATENT OFFICE

FRANK JOSEPH PILAT AND PAUL ALFRED GALGAN, OF CHICAGO, ILLINOIS

SUPPORTING BRACKET

Application filed June 9, 1928. Serial No. 285,947.

This invention relates to improvements in supporting brackets, as disclosed in our application, Serial No. 679,384, filed December 8, 1923, and has particular reference to a bracket adapted for attachment to window frames, and provided with means for supporting engagement with curtain rods, drapery poles, and hanging flower pots, bird cages, and the like, or any one or more of these articles.

The primary object of the invention is to provide a supporting bracket of the above kind, which embraces the desired qualities of simplicity and durability of construction, as well as efficiency in operation.

Another object of the invention is to provide a supporting bracket of the above character, which may be cheaply and easily manufactured and placed into use.

Still another object of the invention is to provide a bracket of the above kind wherein certain of the article supporting means may be removed when not required for use, so as not to mar the appearance of the window and its surroundings, but which may be readily applied when required for use.

Still another object of the invention is to provide simple and effective means for removably mounting the removable supporting means or members relative to the main member of the bracket.

Other objects will appear as the nature of the invention is better understood, and the same consists in the novel form, combination, and arrangement of parts hereinafter more fully described, shown in the accompanying drawing, and claimed.

In the drawing, wherein like reference characters indicate corresponding parts throughout the several views:—

Fig. 1 is a side elevational view of a supporting bracket constructed in accordance with the present invention.

Fig. 2 is a view similar to Fig. 1, with the removable supporting member or means detached therefrom, and drawn on a smaller scale.

Fig. 3 is an enlarged fragmentary perspective view showing the inner end portion of one of the article supporting members.

Fig. 4 is a view similar to Fig. 3, of the inner end of the other removable article supporting member.

Fig. 5 is a top plan view of a modified form of the main member of the bracket applied to a window frame, and

Fig. 6 is a fragmentary perspective view showing the inner end portion of the bracket member illustrated in Fig. 5.

Referring more in detail to the drawing, and particularly to Figs. 1 to 4 inclusive, the present invention embodies a main bracket member composed of a base plate 5 having end openings 6 for reception of screws or the like, whereby said base plate may be attached to the window frame, and formed with means as at 7, between the openings 6 for supporting reception of a shade roller pintle, which means 7 may consist of an embossed projection of well known form, and provided with an opening 8 in a well known manner.

This main bracket member further includes an arm 9 rigid and preferably integral with the plate 5 as well as extending from one edge of said plate in the plane of the latter, and terminating at its free end in means for supporting reception of an article. Further article supporting arms 10 and 11 are detachably carried by the arm 9, and have their free end portions suitably formed for reception of the particular article which they are adapted to engage.

In the form of the invention shown, the arm 9 has its free end forked or bifurcated as at 12 for supporting reception of one end of a drapery pole, said arm being extended outwardly and upwardly as shown in Fig. 1. As is also shown in the drawings, the arm 10 extends downwardly from the arm 9 and has a hooked free end portion as at 13, for engaging the bail of a flower pot, bird cage, or the like, whereby the desired one of these articles may be suspended from the arm 10.

Also as shown, the arm 11 extends outwardly and upwardly from the arm 9, and terminates in a reduced free end portion or pin 14, adapted to enter the transverse opening in certain types of curtain rods.

As shown clearly in Fig. 2, the inner end portion of the arm 9 is provided with a pair

of spaced notches 15 and 16, that extend downwardly from the upper edge of said arm 9 and that are of a width equal to the thickness of said arms 10 and 11. The inner end of each of the arms 10 and 11 is provided with a laterally extending flange or lug 17 that is provided with a slot 18 extending upwardly from the lower edge thereof, and that is of a width equal to the thickness of the arm 9.

10 It will thus be seen that when the arms 10 and 11 are disposed as shown in Fig. 1, with the flanges or lugs 17 extending transversely of the arm 9 and the portions of the latter below the slots 15 and 16 disposed within 15 the slots 18, the arms 10 and 11 are effectively detachably interlocked to the arm 9 and held against tilting movement, the interlocking engagement being maintained by the weight of said arms 10 and 11, which extend along 20 one side of the contact with the one side of the arm 9 to steady the arms 10 and 11 against sidewise strain or movement.

This form of bracket is adapted to be especially attached to the inner face of a window frame, and is found most desirable in certain instances, but should it be necessary to attach the bracket to the window frame in the plane of the window, the main member of the bracket may be modified as shown in Figs. 5 25 and 6. This modification consists simply in eliminating the openings 6 in the base plate 5 and providing the inner edge of the base plate 5 with a lateral flange 9, adapted to flatly engage the window frame in the plane 30 of the window as shown in Fig. 5, and to be secured to the latter in this position by means of screws or the like, the flange 19 being provided with openings through which said screws may be passed. Otherwise, the construction of the main member of the bracket 35 is the same in this form of the invention, as in the form shown in Fig. 1.

Obviously, either one or both of the arms 10 and 11 may be employed with the arm 9, 40 or said arm 9 may be employed alone, at which time, the arms 10 and 11 may be readily removed. It is also noted that no special skill or tools are required in the use of the device, particularly for effecting attachment of the 45 arms 10 and 11 to the arm 9.

The device is useful in its entirety as it is often desirable to simultaneously support a shade, curtain, and drapery in front of the 50 same window, while at the same time, the need is also presented for a supporting bracket to suspend hanging flower pots or baskets, bird cages or the like.

The present device provides for these exigencies without the necessity of a plurality of separate brackets independently attachable to the window frame, which is objectionable for various reasons, including the marring effect of such separate brackets, upon the 55 window frame.

Having thus described our invention, what we claim as new is:—

A support of the class described comprising a bracket arm formed at its inner end with an attaching head for connection to a window frame, and at its outer end with an article supporting seat, said arm having a notch extending downwardly from its upper edge and adjacent its inner end, and an article supporting arm having a lateral slotted lug adapted to cooperate with the notched portion of the bracket arm for holding said arms in interlocked engagement, and a hook on the outer end of the article supporting arm for suspending an element.

In testimony whereof we affix our signatures.

FRANK JOSEPH PILAT
PAUL ALFRED GALGAN.
